UNITED STATES PATENT OFFICE.

GEOEGE W. WALLACE, OF EAST ST. LOUIS, ILLINOIS.

APPARATUS FOR DISTILLING CARBONACEOUS MATERIALS.

1,358,662.

Specification of Letters Patent.

Patented Nov. 9, 1920.

Application filed August 8, 1918. Serial No. 248,614.

To all whom it may concern:

Be it known that I, GEORGE W. WALLACE, a citizen of the United States, residing at East St. Louis, Illinois, have invented a certain new and useful Improvement in Apparatus for Distilling Carbonaceous Materials, of which the following is a full, clear, and exact description, such as will enable others skilled in the art to which it appertains to make and use the same.

This invention relates to apparatus for distilling carbonaceous materials, and particularly to distilling apparatus of the type that are provided with vertically-disposed retorts.

The main objects of my present invention are to provide an efficient distilling apparatus of simple design that insures the recovery of the maximum quantity of oil contained in the carbonaceous material being distilled; that enables the residue to be quickly removed from the retorts at a low cost and without subjecting the workmen to the discomfort incident to discharging the residue from vertical retorts of the kind now in general use and which overcomes the necessity of providing an elevated supporting structure of steel or expensive masonry for the retorts.

Another object is to provide a coal distilling apparatus in which the coke is moved upwardly out of the retort and thereafter conveyed to a point some distance from the retort, where it is quenched or cooled, the apparatus preferably being provided with means for protecting the coke from the atmosphere while it is being conveyed away from the retort and while it is being quenched, thereby preventing oxidation of the coke and also eliminating the smoke nuisance incident to the production of coke or the manufacture of gas.

And still another object is to provide a vertically-disposed retort in which the carbonaceous material being distilled is sustained by a member that is moved positively upwardly through the retort at the termination of the distilling operation, thereby insuring the removal of the residue quickly and completely, owing to the fact that the residue is discharged from the retort by a positively actuated mechanical means in-

stead of by gravity, as in the vertical retorts now in general use. Other objects and desirable features of my invention will be hereinafter pointed out.

Figure 1 of the drawings is a vertical sectional view of an apparatus constructed in accordance with my invention.

Fig. 2 is an enlarged vertical sectional view of one of the retorts, taken on the line 2—2 of Fig. 1.

Fig. 3 is a vertical sectional view, illustrating another form of retort; and

Fig. 4 is a vertical sectional view, illustrating another way of forming a gas-tight joint between the retort and the removable cap or cover that forms a closure for the upper end of the retort.

My improved apparatus can be successfully used for distilling various kinds of carbonaceous materials, but it is particularly adapted for use in distilling coking coals and carbonaceous materials that fuse into a homogeneous mass. In its simplest form it comprises a vertically-disposed retort whose upper and lower ends are sealed or cut off from the atmosphere during the distilling operation, means for applying heat externally to said retort, a perforated take-off duct combined with said retort in such a manner that all of the gases, vapors and liquids evolved in the distilling operation will travel inwardly into said take-off duct through the coolest portion of the material in the retort and then flow downwardly through said take-off duct to a discharge pipe leading away from the apparatus, and means arranged above the retort for moving the take-off duct and the residue of the distilling operation upwardly out of the retort. The apparatus can be provided with either one or a plurality of retorts, and when it is used for distilling coking coals it is preferably provided with a member that protects the coked residue of the distilling operation from the atmosphere while said coked residue is being conveyed away from the retort to the point where it is quenched or cooled.

Referring to the drawings which illustrate the preferred form of my invention, A designates a plurality of vertically-disposed retorts that are adapted to be filled

with coking coal or other carbonaceous material containing oil that can be extracted by a distilling operation, said retorts being mounted in a suitable supporting structure 5 1, and each retort being surrounded by a combustion chamber α to which products of combustion from any suitable source are supplied. Each of the retorts A consists of a cylindrical shell 2 tapered inwardly slightly 10 from its upper toward its lower end and provided with a bottom, formed preferably by a contracted portion 2^a of inverted cone shape. A take-off duct B consisting of a perforated member of cylindrical form is 15 arranged at the center of the retort, the upper end of said take-off duct being closed and the lower end of said take-off duct communicating with a discharge pipe 3 in which a suction is created by some suitable means 20 during the distilling operation. The retort is provided with a removable cap or cover that forms a closure for the upper end of the retort during the distilling operation, said cover being so constructed that a gas-tight joint is formed between same and the 25 upper edge of the retort so as to seal the upper end of the retort or cut it off from the atmosphere during the distilling operation. In the form of my invention illustrated in 30 Fig. 2 the cover 4 is provided with a depending flange 4^a that projects into an annular well 2^b on the upper end portion of the retort that is filled with water or some other suitable liquid, thus producing a liquid seal 35 for the removable cover 4. In the form of my invention illustrated in Fig. 4 a gasket 5^a of some suitable material is arranged between the upper edge of the retort and the cover 4, and means is provided for securely 40 clamping the cover in position, the clamping means shown in Fig. 4 consisting of a yoke 6 and an operating screw 6^a of conventional form. The take-off duct B can either be connected to or carried by the 45 movable cover 4 of the retort, or said take-off duct can consist of a separate unit that is withdrawn from the retort after the cover 4 of the retort has been removed. Therefore, in Fig. 2 of the drawings I have shown the 50 take-off duct B connected at its upper end to the removable cover 4 so that both the cover and the take-off duct can be removed at one operation, and in Figs. 3 and 4 I have illustrated the take-off duct as consisting of 55 a single unit separate and distinct from the cover 4 and having no direct connection with same. When the take-off duct is formed as a separate unit, as shown in Figs. 3 and 4, it is provided with a top wall or 60 portion 7 that forms a closure for the upper end of the take-off duct. If desired, the take-off duct can consist of a cylindrical member whose upper end is connected with the removable cover 4 of the retort, said 65 cover serving as a closure for the upper end

of the take-off duct. Said take-off duct is provided with numerous orifices y through which the gases, vapors and oils evolved in the distilling operation are drawn inwardly into the take-off duct by the suction produced in the discharge pipe 3 with which the lower end of the take-off duct communicates, said orifices y being so positioned that the topmost row of orifices will be below the level of the carbonaceous material in the 70 retort, thereby insuring all of the gases, vapors and liquids evolved in the distilling operation traveling through the coolest portion of the material in the retort and thence into the take-off duct in escaping from the 75 retort.

It is essential that a tight joint be formed between the lower end of the take-off duct B and the bottom 2^a of the retort, and while this can be effected in various ways, I have 80 found that a gas-tight joint can be formed between said parts by providing the lower end of the take-off duct B with a beveled or tapered edge z that rests upon the tapered bottom 2^a of the retort when the take-off 85 duct B is in operative position. The take-off duct B is provided adjacent its lower end with a laterally-projecting flange 8 whose peripheral edge preferably fits snugly against the inner face of the side wall of 90 the retort when said take-off duct is in operative position, said flange 8 serving as the sustaining means for the carbonaceous material in the retort and being arranged in sufficiently close proximity to the bottom 95 row of orifices y in the take-off duct to eliminate the possibility of any liquids collecting and remaining in the lower end portion of the retort. The flange 8 on the take-off duct virtually forms the bottom of the 100 retort, and in view of the fact that said flange is rigidly connected to the take-off duct, it is obvious that when the take-off duct B is moved upwardly through the retort, during the operation of withdrawing 105 the take-off duct from the retort, the residue of the coking operation will be simultaneously discharged or removed from the 110 retort.

Any suitable means can be used for withdrawing the take-off ducts from the retorts and arranging said take-off ducts in operative position preparatory to charging the retorts, but I prefer to provide the apparatus with an overhead track 9 on which a crane 115 10 travels, said crane being equipped with a hoisting apparatus 11. At the termination of the distilling operation the crane 10 can be moved into operative position above the retort whose charge has been distilled, and 120 the cover 4 of said retort can then be removed quickly by simply inserting the hook 12 on the hoisting cable 11 in an eye on the removable cover of the retort and then pulling the cable in a direction to move the 125 130

cover 4 upwardly. If the take-off duct B is connected to the cover 4, only one operation is required to remove the cover and also withdraw the take-off duct and the residue 5 of the distilling operation from the retort. If the take-off duct is formed as a separate unit, however, as illustrated in Figs. 3 and 4, it is necessary to first remove the cover of the retort and then insert the hoisting 10 hook 12 in an eye or other suitable device 7^a on the upper end of the take-off duct and then operate the cable so as to move the take-off duct and the coked residue supported by the flange 8 on said take-off duct upwardly out of the retort. 15

The apparatus is of course provided with some suitable means for closing the discharge pipe 3 prior to the operation of disconnecting the take-off duct from said discharge pipe, said means consisting of a liquid seal or a quick-acting valve 3^a, as 20 illustrated in Fig. 1.

After the take-off duct B and the mass of coked material that surrounds same has been withdrawn from the retort, the crane 25 10 is moved on the overhead track 9 to a point some distance away from the retort, where the coked mass surrounding the take-off duct is quenched and then discharged or removed from the take-off duct in any suitable 30 manner. Thereafter, the take-off duct is returned to the retort by the crane 10 and lowered into the retort by slackening the cable 11, the material being dumped into the open upper 35 end of the retort after the take-off duct has been arranged in operative position. In order that the coked material will be protected from the atmosphere while it is being conveyed away from the retort, I have 40 provided the apparatus with a hollow member 14 consisting of a cylindrical shell open at its lower end and closed at its upper end, as shown in Fig. 1, said shell being suspended by any suitable means from the crane 10. When the crane is moved into 45 operative position above the retort preparatory to withdrawing the take-off duct and the residue of the distilling operation, as previously described, the shell 14 will be brought 50 into alignment with the retort, owing to the fact that said shell is suspended from the crane. Consequently, when the take-off duct B is thereafter moved upwardly out of the retort, said take-off duct and the coked residue sustained by the flange 8 on the take-off duct will be positioned 55 within the shell 14, the top wall of said shell being provided with an opening through which the hoisting cable 11 and the hook thereon can be lowered into position 60 to be engaged with the removable cover of the retort or the device at the upper end of the take-off duct, depending upon whether the take-off duct is connected with the cover

of the retort or formed as a separate unit. 65 When the take-off duct and the coked residue sustained by same is being conveyed away from the retort, the shell 14 protects the coked material from the atmosphere, thereby preventing it from oxidizing and 70 also eliminating the smoke nuisance usually connected with the production of coke or manufacture of gas. The shell 14 protects the coked material from the atmosphere, and it can be so designed that it tends to 75 prevent said coked material from dropping off the flange 8 on the take-off duct while said material is being withdrawn from the retort and while it is being conveyed to the point where it is to be quenched or stored. 80 The shell 14 can either be mounted on the crane 10 in such a manner that it can be lowered into close proximity to the upper end of the retort during the operation of withdrawing the take-off duct B and thereafter raised high enough to clear the covers on the other retorts, or it can be provided at its lower end with a telescoped portion 14^a. In practice I prefer to quench or cool 85 the coked material by admitting water or steam into the shell 14 prior to the operation of discharging the coked material from the take-off duct.

An apparatus of the construction above described has many features which make it 95 a decided improvement on the apparatus heretofore in use for distilling carbonaceous materials; it insures the recovery of the maximum quantity of oil contained in the carbonaceous material being distilled, due 100 to the fact that it is so constructed that all of the gases, vapors and liquids evolved in the distilling operation travel through the coolest portion of the material in the retort in escaping into the take-off duct down 105 which said gases, vapors and liquids are drawn by the suction in the discharge pipe 3 which communicates with the lower end of the take-off duct; it materially reduces the time and cost of discharging the residue 110 from vertical retorts and eliminates the discomforts to the workmen incident to discharging vertical retorts of the kind now in general use, owing to the fact that the residue is moved upwardly out of the upper 115 end of the retort and then conveyed away from the retort by means of an overhead crane equipped with a hoisting apparatus, and it overcomes the necessity of providing a supporting structure for the retorts of 120 steel or expensive masonry, owing to the fact that it is not provided with a pit arranged beneath the retorts into which the residue from the retorts is discharged, as in the vertical retort apparatus heretofore in 125 use. The process disclosed herein is claimed in my co-pending application Serial No. 271,825.

Having thus described my invention, what I claim as new and desire to secure by Letters Patent is:

1. An apparatus for distilling carbonaceous materials, comprising a vertically disposed retort provided with a bottom, a perforated take-off duct arranged inside of said retort at the center of same with its lower end contacting with the bottom of the retort, a suction pipe in sealed communication with the lower end of said take-off duct, a flange projecting laterally from said take-off duct and terminating within the retort for sustaining the material being distilled, and means arranged above the retort for withdrawing the take-off duct together with the residue of the distilling operation upwardly through the retort.
2. An apparatus for distilling carbonaceous materials, comprising a vertically disposed retort tapered inwardly slightly from its upper toward its lower end and provided with a bottom, a perforated take-off duct in said retort adapted to be withdrawn upwardly through the retort and arranged so that the lower end of same rests on the bottom of the retort, and a laterally projecting flange on said take-off duct whose peripheral edge fits snugly against the inside of the retort, said flange serving as a support for the material being distilled.
3. An apparatus for distilling carbonaceous materials, comprising a vertically disposed retort provided at its lower end with a contracted portion, a suction pipe communicating with said contracted portion, a perforated take-off duct in said retort whose lower end is sealed or joined by a tight joint to the contracted portion of the retort, and means on said take-off duct for sustaining the material being distilled, said means and said take-off duct being adapted to be moved upwardly through the retort at the termination of the distilling operation.
4. An apparatus for distilling carbonaceous materials, comprising a vertically disposed retort provided at its lower end with a contracted portion of tapered form, a removable cover for the upper end of said retort, a perforated take-off duct in said retort whose lower end is tapered or beveled so that it will bear snugly against the contracted portion of the retort, a suction pipe that communicates with the lower end of said take-off duct, and means arranged between the take-off duct and the side wall of the retort for sustaining the material being distilled, said means and take-off duct being adapted to be moved upwardly through the retort at the termination of the distilling operation.
5. An apparatus for distilling carbonaceous materials, comprising a vertically disposed retort that is tapered inwardly

slightly from its upper toward its lower end, a removable cover for the upper end of said retort, a perforated take-off duct in said retort closed at its upper end and having its lower end communicating with a suction pipe, and a laterally projecting flange on said take-off duct for supporting the material being distilled and having its peripheral edge bearing snugly against the inner side of the retort, said take-off duct being adapted to be moved upwardly through the retort so as to discharge the residue of the distilling operation.

6. An apparatus for distilling carbonaceous materials, comprising a vertically disposed retort tapered inwardly slightly from its upper toward its lower end and provided at its lower end with a contracted portion, a suction pipe communicating with the contracted portion of the retort, a perforated take-off duct in said retort adapted to be withdrawn upwardly through the retort and provided at its lower end with a beveled edge that rests upon the contracted portion of the retort, and a laterally projecting flange on said take-off duct for supporting the material being distilled and having its peripheral edge bearing snugly against the inner surface of the side wall of the retort.

7. An apparatus for distilling carbonaceous materials, comprising a vertically disposed retort, a device in said retort for sustaining the material being distilled, means for moving said device together with the residue of the distilling operation upwardly out of the retort and to the place where the residue is to be stored or treated, and means attached to said moving device for protecting the residue from the atmosphere while it is being conveyed away from the retort.

8. An apparatus for distilling carbonaceous materials, comprising a vertically-disposed retort, a vertically-movable structure in said retort for sustaining the material being distilled, means for completely withdrawing said structure together with the residue thereon upwardly out of the upper end of the retort, and then conveying said structure away from the retort, and a hollow member adapted to be arranged above the retort in vertical alinement with same so as to receive said vertically movable structure and the residue carried by same.

9. An apparatus for distilling carbonaceous materials, comprising vertically disposed retorts, an overhead track structure arranged above the retorts, vertically movable devices in said retorts for sustaining the material being distilled, a movable carrier on said track structure, means combined with said carrier for withdrawing the residue in said retorts upwardly through the retorts, and a hollow member on said carrier into which the vertically movable device of

a retort and the residue sustained by same is adapted to be moved during the operation of discharging the residue from the retort.

10. An apparatus for distilling carbonaceous materials, comprising vertically disposed retorts, perforated take-off ducts in said retorts, suction pipes communicating with the lower ends of said take-off ducts, removable covers for the upper ends of said 10 retorts, means on said take-off ducts for sus-

taining the material being distilled, an overhead track structure arranged above the retorts, and means carried by said track structure for enabling the take-off duct of any retort together with the residue of the distilling operation to be withdrawn upwardly through the retort and conveyed away from the retort. 15

GEORGE W. WALLACE.
